UNITED STATES PATENT OFFICE.

PETER GENDRON, OF TOLEDO, OHIO.

DESIGN FOR A BICYCLE-PEDAL FRAME.

SPECIFICATION forming part of **Design No. 25,031**, dated **December 31, 1895**.

Application filed August 24, 1895. Serial No. 560,440. Term of patent 7 years.

To all whom it may concern:

Be it known that I, PETER GENDRON, a citizen of the United States, residing at Toledo, in the county of Lucas and State of Ohio, have 5 invented and produced a new and original Design for Bicycle-Pedal Frames, of which the following is a specification, reference being had therein to the accompanying drawings.

10 Figure 1 is a side elevation of a bicycle-pedal frame embodying my design. Fig. 2 is a top plan view thereof, and Fig. 3 is an end elevation.

15 The push-frame is formed with two similar opposed portions A. In plan each of these portions is substantially rectangular with the curved or rounded corners a. From the corners a the ends of the two portions A curve

gradually away from each other to the central points c, thus causing the frame to present in 20 side elevation a double canoe shape.

E are the ends curved as shown at d toward the portions A. Centrally of the ends E are the rings or annular sections F.

The essential feature of the design is the 25 pedal-frame, as shown and described.

What I claim as my invention is—

The design for a bicycle pedal frame, substantially as herein described and shown.

In testimony whereof I affix my signature 30 in presence of two witnesses.

PETER GENDRON.
